(57) **CLAIM**

The ornamental design for the chair having the appearance of a Great White shark, as shown and described.

DESCRIPTION

FIG. 1 is a perspective view of the chair having the appearance of a Great White shark of the invention;

FIG. 2 is a side view of the chair having the appearance of a Great White shark, it being understood that the opposite side is a mirror image thereof;

FIG. 3 is a front view of the chair having the appearance of a Great White shark;

FIG. 4 is a rear view of the chair having the appearance of a Great White shark;

FIG. 5 is a top view of the chair having the appearance of a Great White shark; and,

FIG. 6 is a bottom view of the chair having the appearance of a Great White shark.

The broken line showing of the mouth and teeth in FIG. 1 is for illustrative purposes only and forms no part of the claimed design.
